UNITED STATES PATENT OFFICE.

DOMENICK CAPRAROLA, OF BALTIMORE, MARYLAND, ASSIGNEE OF ONE-HALF TO
DAVID S. GROSS, OF BALTIMORE, MARYLAND.

COAT.

Application filed May 28, 1927. Serial No. 194,892.

The present invention relates to coats and the method of making the same and more particularly to coats of substantially seamless construction.

Heretofore in the manufacture of coats of substantially seamless construction, it has been proposed to provide a coat blank comprising integral front and rear panels separated by cut-out portions. Such cut-out portions have been made in such a manner as to necessitate lifting one panel with respect to the other in order to properly seam the edges of the panels. This results in a coat of improper fit, or makes necessary stretching of the coat material, or similar operations, in order that the coat shall fit properly. This construction also results in displacing the surface design of the coat material, especially when the design includes cross stripes as in plaid goods. The cut-out portions, as heretofore made, have, furthermore, also been of the wrong shape. For example, according to one known method, the front edge of the cut-out portion is approximately straight, the rear edge of the cut-out portion being concave. This construction does not permit the proper shaping of the back of the coat and also has a tendency to result in wrinkles being formed in the vicinity of the seams joining the front and rear panels.

According to the present invention the coat blank is provided with cut-out portions between the front and rear panels, the upper ends of the edges of each cut-out portion being in horizontal alignment so as to obviate the necessity for lifting either of the panels for properly making the seams. The front edge of the cut-out portion is made convex and the rear edge is made concave in order to obtain the desired shaping of the coat to the body of the wearer, more especially at the back, and to prevent wrinkling. To further provide for a better fit and prevent wrinkling or folding, a dart-like cut-out is provided near the lower end of the rear edge of the above described cut-out portion.

The invention will be explained more in detail by reference to the accompanying drawings forming a part of this specification.

In the drawings:

Fig. 1 is a view of a coat blank lying flat as cut;

Fig. 2 is a similar view of a blank for a coat of a different type.

Referring to Fig. 1, the coat blank comprises front panels 10 and 11 and an intermediate or rear panel 12. The general contour of the blank will vary, of course, in accordance with the style of coat to be made. Arm hole recesses 13 and 14 are formed in the blank, as shown, cut-out portions 15 and 16, which are substantially crescent-shaped, extend downwardly from the lower rear ends of the arm-hole recesses to a point near the location of the side pockets 17 and 18.

As the cut-out portions at both sides of the coat blank are the same, only one will be described. The cut-out portion 15 comprises front edge 19 which is convex, and a rear edge 20 which is concave, the upper ends of these edges meeting at a common point 21. The lower end of the edge 19 terminates at the point 19^a, and the lower edge 20 terminates at the point 20^a.

At the lower ends of the cut-out portions 15 and 16, there are provided triangular or dart-like cut-outs 22 and 23, identical in construction. The cut-out 22 is formed along the front edge 19 of the cut-out portion 15 and along angular lines extending rearwardly from the points 19^a and 20^a to the point of intersection 22^a, the lines 19^a—22^a being substantially horizontal.

In properly assembling the coat blank, the front and rear edges of the cut-out portions 15 and 16 are joined together to form a seam. The meeting point 21 of the edges 19 and 20 is spaced by widths of the material 21^a from the edges of the arm-hole recess 13 to permit infolding of the edges to form the seam. The seam is started at the meeting point 21 and continued downwardly, meeting lines or notches 19^b—20^b, 19^c—20^c, and 19^d—20^d, being provided to facilitate the sewing operation to form a good seam free from wrinkles. When the seam is formed, the lower end 20^a of the edge 20 will meet the lower end 19^a of the edge 19, and the line 20^a—22^a will meet the line 19^a—22^a, and since the latter is slightly longer than the former, a cut-out or fold 24 is provided, there being a similar device 25 for the other side of the blank.

Referring to Fig. 2, there is shown a modified construction suitable for a coat of a different style, which may be a so-called

sport coat. The construction is generally the same as that shown in Fig. 1, the corresponding parts being designated by the same reference characters primed. However, in coats of this type the back is usually more close fitting and is provided with plaits such as 26 and 27 and a belt 28. For this reason, the cut-out portions 15' and 16' need not be as large as the cut-out portions 15 and 16, and the slopes of the front and rear edges 19' and 20' need not be as steep as the slopes of the edges 19 and 20.

While I have shown the invention applied specifically to only two types of coats, it will be understood that the invention is likewise applicable to coats of other types. It will also be understood that the coat blank may be either the pattern which is to be followed in cutting the material or may be the material itself cut as indicated herein.

Having thus described my invention, what is claimed and desired to be secured by Letters Patent of the United States is:

1. A coat blank having an arm opening and integral front and rear panels separated by a cut-out portion having edges the upper ends of which meet at said arm-opening and extend downwardly, the front edge of said cut-out portion being convex and the rear edge of said cut-out portion being concave, the lower end of said concave edge terminat-

ing short of the lower end of said convex edge.

2. A coat blank having an arm opening and front and rear panels each separated by a crescent-shaped cut-out portion, the front edge of said cut-out portion being convex toward said rear panel and the rear edge of the cut-out portion being concave toward said rear panel, and a dart-like opening at the base of said crescent-shaped opening.

3. A coat blank having an arm opening and front and rear panels separated by a cut-out portion having edges the upper ends of which meet at said arm opening and which extend downwardly the front edge of said cut-out portion being convex and the rear edge of said cut-out portion being concave, the lower end of one edge terminating short of the lower end of the other edge, said rear panel having plaits cooperating with said cut-out portions to form a blank for a coat of the desired fit at the back of the wearer.

4. A coat comprising a coat blank having front and rear panels separated by a cut-out portion, the front edge of said cut-out portion being convex toward said rear panel, and the rear edge of said cut-out portion being concave toward said rear panel.

In testimony whereof, I hereunto affix my signature.

DOMENICK CAPRAROLA.
